AIR-PRESSURE BRAKE.

1,182,774.

Specification of Letters Patent.

Patented May 9, 1916.

Application filed December 12, 1913. Serial No. 806,320.

To all whom it may concern:

Be it known that I, PAUL KORT, citizen in the German Empire, residing at Hanover, Germany, have invented certain new and 5 useful Improvements in Air-Pressure Brakes, of which the following is a specification.

This invention relates to improvements in air pressure brakes especially those used on 10 railway trains and its object is to reduce the quantity of compressed air which must be supplied from the pump when working.

Its object is further to cheapen the operation and to increase the efficiency and quick- 15 ness of action of the brake.

To meet these ends according to the present invention, the compressed air at the points where it is admitted to the apparatus, which may be either at the driver's valve or 20 at the triple valve, is caused to draw in through a suitable suction device fresh air to supplement the supply from the pump.

The invention is illustrated by way of example in the accompanying drawings in 25 which—

Figure 1 shows the invention applied to the driver's valve in an air pressure brake system, this figure being a section on the line A—B of Fig. 2. Fig. 2 is a section on 30 the line C D of Fig. 1. Fig. 3 shows the invention applied to the triple valve located between the auxiliary reservoir and the brake cylinder, this figure being a section on the line E—F of Fig. 4. Fig. 4 is a section 35 on the line G H of Fig. 3.

In carrying the invention into effect according to the form shown in Figs. 1 and 2, the chamber *b* of the driver's valve *a* is connected in the known manner to the 40 main reservoir. When the valve *e* is opened by the driver or operator, compressed air passes from the chamber *b* through the valve *e* and enters at *g* into a suction device which is here shown as a double coni- 45 cal nozzle. This suction device is surrounded by an annulus *m* in communication with the outer air. The compressed air passing through the suction device *c* draws air from this annulus which air passes from the 50 driver's valve *a* to the main train pipe past the pressure regulating valve *n*. The compressed air passes through the pressure regulator *n* until the train pipe reaches the normal working pressure. The annulus *m* is

connected to the outer air through a passage 55 *k*, chamber *i* and non-return valve *h*.

For the purpose of preventing entry of dirt the sieve *o* is inserted in the chamber *i*. By arranging the air suction device in the driver's valve as described this suction de- 60 vice can be properly controlled and ob- served by the operator when operating the driver's valve. The invention however may be applied at any point where the flow of air under pressure is initiated on operating 65 the valves either to apply or put off the brakes.

According to the form shown in Figs. 3 and 4 the suction device *c* is inserted in the control valve located between the auxiliary 70 reservoir and the brake cylinder of a pressure brake system. This control valve, usually called a triple valve *p*, is as is well known interposed between the auxiliary or reservoir attached to each brake cylinder 75 and the brake cylinder itself. The construction of the triple valve is not fully illustrated in the figures as this construction has no bearing on the present case.

The conduit or passages *q* *r* in the valve 80 form part of the connection from the auxiliary reservoir to the brake cylinder. The suction device *c* according to the present in- 85 vention is interposed in this path. As before, this suction device comprises a double nozzle passage. The outer air is drawn through the annulus *m* past the non-return valve *h* and *c* as in Fig. 3. In the normal or non-working position of the valve the for- 90 ward opening of the suction device is closed by means of the small valve *s* which is con- 95 nected to and operates with the slide valve *t* which is controlled in the known manner by the piston *v*. The connection between the slide *t* and valve *s* is effected in such a man- 100 ner that the passage of the air to the air suction device remains unthrottled.

For the purpose of quick action it is nec- 100 essary to conduct the air pressure through as large passages as possible to the brake cylinder. The suction device with its narrow con- 105 duct is not sufficient for the rapid conduction of the air from the auxiliary pressure cylinder into the brake cylinder. In the triple valve sleeve there is therefore pro- vided a passage *x* which in the quick acting position of the control piston *v* is opened by the slide *t* and thereby connects the aux-

iliary pressure reservoir through the passages q, r, x, y of Fig. 4 directly to the brake cylinder. The passages x, y thus form a by-pass which permits part of the air to 5 pass to the brake cylinder without going through the suction device. The brake cylinder is connected to the nipple z . The provision of this by-pass it will be understood does not preclude a certain amount of air 10 passing through the narrow opening of the suction device c . In the off position of the slide valve the by-pass x, y Fig. 3, is connected to the outer air through the cavity t' and port x' so that a rapid exhaust of the 15 air from the brake cylinder may be effected. This completely avoids any delay in the loosening of the brakes owing to retardation in the escape of the air owing to the narrow orifice in the suction device.

20 It is possible to use the suction device both in the driver's valve and in the local control or triple valve simultaneously without in any way departing from this invention. This is to say the valve according to 25 Figs. 1 and 2 would be used as a driver's valve and the valve according to Figs. 3 and 4 would be used at the separate brake cylinders.

I claim:

- 30 1. In an air pressure brake system, a triple valve casing, a conduit in said valve casing and leading from the auxiliary reservoir to the brake cylinder, and an air suction device in said conduit.
- 35 2. In an air pressure brake system, a triple valve casing, a conduit in said casing, a control piston, a slide valve operated thereby, a by-pass conduit to said first mentioned conduit and controlled by said valve, 40 a suction device also controlled by said valve and interposed in said first mentioned conduit between the connections thereto and the by-pass, substantially as described.
- 45 3. In an air brake system, the combination with a triple valve, of means operable upon a movement of the triple slide for introducing atmospheric air into the brake cylinder to supplement the supply from the auxiliary reservoir.
- 50 4. In an air brake system, the combination with a triple valve, of an automatic air suction device interposed between the slide valve chamber and the brake cylinder, a valve normally closed when the slide valve 55 is in release position for controlling the admission of air to the suction device, means connecting the said valve with the triple slide valve, whereby upon a movement of the slide valve to service position the suction 60 valve will be opened.
- 55 5. In an air brake system, the combination with a triple valve, of an air suction device interposed between the slide valve chamber and the brake cylinder and adapted 65 to operate during service position of the

slide valve to supplement the auxiliary reservoir air as it passes to the brake cylinder with an additional amount of atmospheric air.

6. In an air brake system, the combination with a triple valve, of an air suction device interposed between the slide valve chamber and the brake cylinder, means operated by the movement of the slide valve for controlling the passage of air to the suction device, the triple valve casing having a passage, said passage communicating with the suction device and the atmosphere, and automatic means for controlling the flow of air in the passage.

7. In an air brake system, the combination with a triple valve of an air suction device interposed between the slide valve chamber and the brake cylinder, means for controlling the passage of air in the suction device, and means operating independently of the suction device for quickly venting and quickly charging the brake cylinder.

8. In an air brake system, the combination with a triple valve of an air suction device interposed between the slide valve chamber and the brake cylinder, a valve controlling the passage of air through the suction device, and means for opening an auxiliary passage between the brake cylinder and the atmosphere independent of the suction device for quickly venting the brake cylinder during release position.

9. In an air brake system, the combination with a triple valve, of an air suction device interposed between the slide valve chamber and the brake cylinder, a valve in the suction device operated by the movement of the slide valve and normally closed when the slide valve is in release position, the triple valve casing having a passage leading from the brake cylinder and opening into a port in the slide valve seat and a second passage having a port in the valve seat and communicating with the atmosphere, the slide valve having a cavity which is adapted to connect the two aforesaid ports when the slide valve is in release position whereby the brake cylinder will be quickly exhausted.

10. In an air brake system, the combination with a triple valve, of an air suction device interposed between the slide valve chamber and the brake cylinder, a valve controlling the admission of auxiliary reservoir air into the device, and means operated by the movement of the triple valve piston for opening an auxiliary passage between the slide valve chamber and the brake cylinder when said triple piston is in its emergency position for quickly charging the brake cylinder independent of the suction device.

11. In an air brake system, the combination with a triple valve, of an air suction

- device interposed between the slide valve chamber and the brake cylinder, a valve controlling the passage of air to the device, a passage independent of the suction device leading from the brake cylinder to a port in the slide valve seat, whereby upon a movement of the slide valve to emergency position the port will be opened and the brake cylinder quickly charged.
12. In an air brake system, the combination with a triple valve, of an air suction device interposed between the slide valve chamber and the brake cylinder and comprising a tubular member having a longitudinal reduced passage therein, said passage

opening in a relatively wider longitudinal passage in the tubular member, said member having a plurality of transverse openings in its sides, said openings communicating with the wider passage and located adjacent the end of the reduced passage, said transverse openings also communicating with an annular cavity in the triple valve casing, said cavity communicating with the atmosphere and a check valve controlling said communication. 20
